(57) **CLAIM**

The ornamental design for a guide for a sealant applicator nozzle, as shown and described.

DESCRIPTION

FIG. 1 is an isometric view of a first embodiment of a guide for a sealant applicator nozzle, showing my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is an isometric view thereof coupled to a sealant applicator nozzle;

FIG. 9 is a front elevational view thereof coupled to a sealant applicator nozzle;

FIG. 10 is an isometric view thereof showing the rotatable cylinder in an alternate position;

FIG. 11 is a front elevational view thereof showing the rotatable cylinder in an alternate position;

FIG. 12 is an isometric view of a second embodiment of a guide for a sealant applicator nozzle, showing my design;

FIG. 13 is a front elevational view thereof;

FIG. 14 is a rear elevational view thereof;

FIG. 15 is a right side elevational view thereof;

FIG. 16 is a left side elevational view thereof;

FIG. 17 is a top plan view thereof;

FIG. 18 is a bottom plan view thereof;

FIG. 19 is an isometric view thereof showing the rotatable cylinder in an alternate position; and,

FIG. 20 is a front elevational view thereof showing the rotatable cylinder in an alternate position.

The rotatable cylinder is shown in alternate positions to indicate that the cylinder is fully rotatable about the longitudinal axis of the post. The broken line showing in the Figures illustrates environment and forms no part of the claimed design.
